UNITED STATES PATENT OFFICE.

AUGUST KOTTMANN, OF SOMMERDA, GERMANY, ASSIGNOR TO THE FIRM: RHEINISCHE METALLWAAREN- UND MASCHINENFABRIK, OF DUSSELDORF- DERENDORF, GERMANY.

KEY MECHANISM FOR CALCULATING AND ADDING MACHINES.

Application filed May 12, 1925, Serial No. 29,673, and in Switzerland March 20, 1925.

The key-mechanisms, for calculating and adding-machines are commonly so constructed that abutments of various kinds, directly actuated by the keys, are brought 5 into the path of the racks. These key-mechanisms have the drawback that each stop must be machined individually, rendering the cost of manufacture very considerable, and a replacement of parts, due to 10 damage to the key-mechanisms is difficult.

The object of my invention is to avoid these drawbacks and to provide a key-mechanism for calculating and adding-machines 15 which is simple in construction, and where- 15 by a ready exchange of the individual elements in the event of damage may be effected.

This is achieved by providing the lower 20 end of the keys with toothed wheels of uniform shape, each toothed wheel being provided with a finger projecting laterally of the wheel, and positioned thereon in accordance with the value of its corresponding key, and by the provision of a device, 25 for each toothed wheel, for locking it in its initial position, and of a stop for limiting the rotation of the wheel.

An embodiment of the invention is illustrated, by way of example, in the accompanying drawings, in which:—

Fig. 1 is an elevation partly in section, 30 of key-mechanism according to the invention.

Fig. 2 shows two of the keys in elevation, 35 one of them being depressed, and

Fig. 3 is a side elevation of one of the keys with its toothed wheel.

In the frame 1 of the machine the keys 2 are guided in usual manner in a cover- 40 plate 3 and a bar 4 situated below. Around each key 2 is a compression spring 5, arranged between a stop on the key, under the cover plate 3, and the guide bar 4. Each key 2 carries at its lower end a toothed 45 wheel 6, all the wheels being of uniform shape and freely rotatable. Each of said wheels is provided with a separate finger 7, projecting laterally of the wheel surface, as may clearly be seen from Figs. 2 and 50 3. The finger 7 may be secured to the toothed wheel, or the latter may be provided with one extended tooth projecting beyond its surface. A stop 8, in the form 55 of a pin, is provided on each key 2 in the

path of its finger 7, by means of which 55 the rotary movement of the toothed wheel is limited. In order to always secure the toothed wheels in their initial position, so that they may correctly engage in the rack during the depression of the key, provision 60 is made on the guide bar 4 of locking devices 9 which, for example, may be pins adapted to engage between the teeth in order to hold the toothed wheel 6 in the desired position. Such a pin could be substituted, for ex- 65 ample, by a spring-pawl or other suitable device.

The operation of the key-mechanism according to the invention is as follows:—

The toothed wheels 6 are set in accord- 70 ance with the value of their correspond- ing keys.

If, for example, as shown in Fig. 2 the key for the numeral "6" is depressed, the corresponding toothed wheel 6 is brought 75 into engagement with the rack 10, and by the subsequent movement of said rack, the wheel 6 is rotated until the finger 7 strikes against the stop 8, whereby, in the given example, since the key for the numeral 6 80 is to be considered, the wheel 6 is advanced to the extent of six teeth. From this moment onward the rack 10 can be moved no further, but remains stationary until the device for returning all the racks into their 85 initial positions forces the racks in the opposite direction and thus returns them to their initial positions. After completion of the calculation operations and during the cancellation, the keys 2 are moved upwards 90 under the action of the springs 5, where- upon the locking devices 9, provided on the bar 4, engage in the corresponding spaces of the teeth of the toothed wheels 6, and lock them in their initial positions, so that 95 they are in the correct position for the next stage of operation.

I claim:

1. An actuating mechanism for calculating machines, comprising, in combination, 100 a key, an operating member, a gear carried by said key for engagement at will with said operating member to be rotated thereby, and a projection on said gear located thereon in accordance with the value of 105 said key and co-operating with said key to limit the rotation of said gear.

2. An actuating mechanism for calculat-

ing machines, comprising, in combination, with the value of said key, and a stop a key, an operating member, a gear carried located on the key and cooperating with by said key for engagement at will with said finger to limit the rotation of said gear. 10
said operating member to be rotated there-
5 by, a finger on said gear projecting later-
ally from the surface thereof, said finger
being located on said gear in accordance

In testimony whereof I have affixed my
signature.

AUGUST KOTTMANN.
